CLAIM

The ornamental design for a head massager, as shown and described.

DESCRIPTION

FIG. 1 is a front perspective view of a head massager, showing my new design;

FIG. 2 is a top perspective view thereof;

FIG. 3 is a rear perspective view thereof;

FIG. 4 is a bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is an enlarged detail view of area 11 in FIG. 1 thereof;

FIG. 12 is an enlarged detail view of area 12 in FIG. 1 thereof; and,

FIG. 13 is an enlarged detail view of area 13 in FIG. 1. The broken lines in the drawings illustrate the portions of the head massager, which form no part of the claimed design. The dot-dash broken lines in the figures depict the boundaries of the enlargements and form no part of the claimed design.
